COMBINED CAMERA AND FLASHGUN

Jay Doblin, Chicago, Ill., assignor to Whitehouse Products, Inc., Brooklyn, N.Y., a corporation of New York

Filed Mar. 21, 1962, Ser. No. 69,362

Term of patent 14 years

(Cl. D61—1)

FIG. 1

FIG. 2

FIG. 4

FIG. 3

FIG. 5

FIG. 7

FIG. 6

FIG. 1 is a top-front isometric view of a combined camera and flashgun showing my new design, with the flashgun detached;

FIG. 2 is a rear elevational view thereof;

FIG. 3 is a bottom plan view thereof;

FIG. 4 is a rear elevational view of the camera with the flashgun attached;

FIG. 5 is a top plan view thereof;

FIG. 6 is a front elevational view thereof; and

FIG. 7 is a right-side elevational view thereof.

I claim:

The ornamental design for a combined camera and flashgun, as shown.
